OLEFIN CONVERSION PROCESS

Arthur L. Jones, Solon, Ohio, assignor to The Standard Oil Company, Cleveland, Ohio
No Drawing. Continuation-in-part of abandoned application Ser. No. 760,991, Sept. 19, 1968. This application Apr. 12, 1971, Ser. No. 136,181
Int. Cl. C07c 3/20

U.S. CL. 260—673

2 Claims

ABSTRACT OF THE DISCLOSURE

An olefin or mixtures of olefins are converted to more complex chemical compounds such as dimers by contact with a liquid metal at an elevated temperature.

Benzene and 1,5-hexadiene are formed on passing a mixture of propylene and air through a molten mass composed of bismuth and tin.

This is a continuation-in-part of my co-pending application Ser. No. 760,991, filed Sept. 19, 1968, and now abandoned.

The present invention relates to the conversion of olefins to more complex compounds and more particularly pertains to the isothermal dehydrodimerization of olefinic hydrocarbons by contacting said olefinic hydrocarbons with a liquid metal at an elevated temperature.

It is believed that the process of the present invention is completely novel and unobvious, and this will become more apparent from the following discussion of prior processes employed for the conversion of olefins to more complex compounds.

Dehydrodimerization of monoolefins has previously been carried out at a temperature above 300° C. in the presence of a catalyst such as an oxide of lead, cadmium, or thallium as described in French Pat. No. 1,473,718. In this prior art process the feed is composed of the monoolefin and oxygen. The presence of oxygen causes the production of carbon dioxide as a by-product. According to this prior art process propylene is converted to 1,5-hexadiene, isobutylene is converted to 2,5-dimethyl-1,5-hexadiene, and alpha-methyl styrene is converted to 2,5-diphenyl-1,5-hexadiene. According to this prior art disclosure the catalytic dehydrodimerization reaction can also be used to convert toluene to benzyl, acetonitrile to succinonitrile and acetic acid to succinic acid.

According to British Pat. No. 1,084,743 relatively high molecular weight dienes are produced by thermal treatment of certain specified monoolefinic compounds. British Patent No. 1,084,743 discloses that compounds of the type

wherein R must be a secondary or tertiary alkyl radical, R₁, R₂ and R₃ are hydrogen, alkyl, etc., can be converted by pyrolysis at a temperature in the range of 660° F. to 1850° F. in the absence of a catalyst to compounds of the type

plus by-products. Oxygen is not necessary in this prior art process, although inert materials such as paraffinic hydrocarbons, benzene, nitrogen, helium and carbon monoxide can be included in the feed. Inert solids may also be used such as magnesia, glass, Pyrex®, quartz, Carborundum and the like.

2

I have discovered a process for converting an olefin or a mixture of olefins to more complex chemical compounds comprising contacting the olefin, optionally with oxygen or an oxygen-containing gas such as air, with a liquid metal or mixture of liquid metals at an elevated temperature, below, above or substantially at atmospheric pressure.

The olefins useful in the instant process are preferably olefinic hydrocarbons having from 2 to 20 carbon atoms.

10 The olefinic hydrocarbons may be monoolefinic or polyolefinic hydrocarbons such as ethylene, propylene, the butylenes, the amylenes, the hexenes, cyclohexene, the heptenes, the octenes, the nonenes, the decenes, the undecenes, the dodecenes and the like; butadiene, isoprene, 15 2,3-dimethylbutadiene, piperylene, 2-neopentyl butadiene-1,3 and the like and others. Most preferred olefinic hydrocarbons are the monoolefinic hydrocarbons having from 2 to 6 carbon atoms.

The liquid or liquified metal useful in this invention can be any metal or alloy which exists as a liquid under the preferred reaction conditions of the process of this invention. Preferred metals which can be used alone or in combination are bismuth and tin.

20 The preferred reaction conditions for the process of this invention are from about 200° C. or lower to 1200° C. or higher and pressures at or near atmospheric, below atmospheric or above atmospheric. Most preferred conditions are from about 350° C. to about 650° C. and about atmospheric pressure. Contact times on the order of 0.2 second up to as long as 3.0 seconds can be used advantageously in this process.

25 The more complex chemical compounds produced in the process of this invention are predominantly linear and cyclic oligomers or low polymers of the starting olefin such as dimers, trimers, tetramers and the like. The main products of the instant process are dimers and trimers of the starting olefin.

30 Preferably the olefin, optionally with molecular oxygen, is passed through a mass of liquid metal in the instant process. A variety of liquid metals and liquid mixtures of metals can be used as isothermal reaction media by passing reactants through a mass of the liquid medium and allowing the resultant bubbles to climb by gravity through the medium. It is also preferred that the feed be 35 efficiently dispersed in the liquid metal for more efficient contact. It is believed that the instant process is carried out under nearly perfect isothermal conditions which is a decided advantage. According to an article by C. F. Cullis, Industrial and Engineering Chemistry, vol. 59, December, 1967, page 21:

40 "Since most oxidation processes are highly exothermic, another important physical consideration is the ease of removal of the heat of reaction, since, if there is a runaway increase of temperature, only complete combustion of the hydrocarbon will take place. To facilitate the 45 maintenance of as nearly as possible isothermal conditions, long narrow catalyst beds are frequently used and the catalyst may also be diluted with an inert solid, perhaps using the greatest dilution at the inlet end where the partial pressure of the reactants are highest."

50 The temperature of the liquid metal used as reaction medium in the instant process can be maintained to a close tolerance because of its excellent heat transfer properties. Thus, it is believed that the instant process is 55 nearly an ideal isothermal process and has none of the "run-away" potential associated with prior art processes.

60 Although the exact mechanism of the chemical reactions which occur in this process are not known with any degree of certainty, it is believed that hydrogen is 65 extracted from the olefins to form radicals and that these 70 radicals combine to form the more complex compound

products. When the process is carried out in the substantial absence of molecular oxygen, the major products are oligomers such as dimers and trimers of the olefin and hydrogen. When appreciable amounts of molecular oxygen are present in the feed, the main products are oligomers and water. When oxygen is used in the feed there are also oxygenated products and carbon oxides produced in minor quantities.

Propylene, for instance, can readily be converted to 1,5-hexadiene by the process of this invention and isobutylene is converted to 2,5-dimethyl-1,5-hexadiene. These diene products may be used for many purposes. Thus, from such dienes there can be manufactured many resins and polymers which are valuable for the preparation of fibers and filaments. The dienes can undergo the oxo reaction to form diols useful as solvents or as intermediates in the manufacture of other resins. The 1,5-dienes can be selectively isomerized to conjugated dienes which have many useful applications, e.g., reaction with maleic anhydride. Typically, 2,5-dimethyl-1,5-hexadiene can be converted to 2,5-dimethyl-2,4-hexadiene. The latter material can be polymerized to high-melting point and high molecular-weight polymers using an appropriate catalyst, e.g., boron trifluoride catalyst.

According to this invention, reaction conditions can be selected whereby cyclic oligomers such as benzene can be produced from propylene and xylenes can be produced directly from isobutylene. In general, very few oxygenated products are produced by this process; however, conditions can be adjusted so that propylene oxide and ethylene oxide can be produced from propylene and ethylene, respectively.

In the following example which will further illustrate this invention, the amounts of all ingredients are expressed as parts by weight unless otherwise indicated.

EXAMPLE

The reactor employed was a large Pyrex® glass tube having a spherical ground glass cap with two entry ports. The bottom section was equipped with a side-arm for product withdrawal. The diameter of the reactor was about two inches and the overall height was about nine inches. The side-arm was located about six inches up from the bottom of the reactor. The depth of the liquid metal in the reactor was usually maintained at about 4½ inches. A Pyrex® glass gas dispersion tube having a "medium" or "coarse" porous tip was used to introduce the reactants into the liquid metal at a point below the surface of the liquid metal. A small stainless steel tube was fit concentrically inside the dispersion tube. Air or oxygen was fed through the outside annulus of the concentric tube arrangement and hydrocarbon gases were fed through the center tube.

The reactants were mixed as they passed through the porous glass tip of the dispersion tube. The mixed gases were passed up through the molten metal as bubbles until they broke through the upper surface of the liquid, where the gaseous products were withdrawn through the side-arm.

The residence time of a bubble of reactants in the liquid metal using the above-described apparatus is about 0.5 second. The time is almost independent of flow rate. Because bubble size is determined by size of the pores in the gas disperser, changes in flow rate produce more or fewer bubbles of about the same size which require about the same time to rise through the melt regardless of the number of them. At very high flow rates bubbles will coalesce to produce larger bubbles which will climb more quickly. Less satisfactory results are obtained under the latter conditions. The most practical way to change residence time (contact time) is to change the height of the liquid metal through which the bubbles rise.

The reactants were contained in pressure gas cylinders. Pressure was reduced through regulator valves and the rate of gas flow to the reactor was controlled by

rotameters. The hydrocarbon regulator pressure was set at 10 p.s.i.g. and air and nitrogen pressures were set at 15 p.s.i.g. The gases may be mixed after coming from the rotameters and before entering the reactor. The reactor was immersed in a radiant heat electric coil furnace, the temperature of which was regulated by a variable transformer and a temperature controller. A thermowell having two thermometers for temperature indication and regulator was located in the mass of liquid metal.

As the product gases came from the reaction zone, they were passed through a glass sample collector. The gas samples were analyzed by gas chromatography and sometimes also by mass spectrometry. The reaction was monitored by means of a vapor fractometer which had two room temperature columns. One column was made up of a 10-foot long, 118-inch tube packed with 13× molecular sieves. This column was capable of resolving hydrogen, oxygen, nitrogen, carbon monoxide and methane. The second column was packed with Chromosorb P (40-50 mesh) having 30 feet impregnated with acetyl acetone and 10 feet with benzyl ether. The second column was capable of resolving C₂, C₃, C₄ hydrocarbons and carbon dioxide.

(A) In this manner a mixture of propylene:air in the mole ratio of 1:2, respectively, was passed through a molten mass composed of one part by weight of bismuth metal and one part by weight of tin metal which was maintained at 1100° F. The propylene:air mixture was fed at the rate of 80 cc. per minute and the gaseous product had the following composition on a weight basis:

	Percent
Propylene	87.36
CO ₂	4.43
CO	0.05
35 Ethylene-ethane	1.06
Methane	0.45
C ₄	0.25
1,5-hexadiene	1.86
Benzene	4.53

This represents a 15% yield based on propylene converted, of 1,5-hexadiene.

(B) A repeat of this procedure with the exception that glass helices were used in the reaction tube in place of the molten metal mixture produced a total per pass conversion of propylene of 75%, giving oxygenated and decomposition products of propylene and no detectable 1,5-hexadiene or benzene.

I claim:

1. The process for converting propylene to 1,5-hexadiene and benzene consisting of bubbling a mixture of propylene, oxygen or an oxygen-containing gas through a catalyst which is a member selected from the group consisting of molten bismuth, molten tin, and mixtures thereof, in the range of from about 350° C. to about 650° C.
2. The process of claim 1 wherein the contact time is from 0.2 up to 3.0 seconds.
